UNITED STATES PATENT OFFICE.

FRANK L. PATTERSON, OF NEW YORK, N. Y.

HOT-WATER TANK.

1,071,570.

Specification of Letters Patent. Patented Aug:26,1913.

Application filed January 15, 1913. Serial No. 742,174.

To all whom it may concern:

Be it known that I, FRANK L. PATTERSON, a citizen of the United States, and a resident of the city of New York, borough of Brooklyn, in the county of Kings and State of New York, have invented a new and Improved Hot-Water Tank, of which the following is a full, clear, and exact description.

The object of the invention is to provide 10 a new and improved hot water tank more especially designed for use in apartment houses, hotels, office buildings, stores, garages and other buildings requiring an ample supply of hot water, and arranged to 15 allow for the expansion and contraction of the steam tubes to insure proper expansion of the exhaust or live steam used as the heating medium, and to readily carry off all the 20 water of condensation without danger of such water accumulating or backing up in the steam tubes.

For the purpose mentioned use is made of 25 an outlet for the hot water, a steam expansion and distributing chamber attached to the shell and connected with a source of 30 steam supply, a condensation chamber attached to the said shell and provided with an outlet for carrying off the water of condensation, the chambers being spaced apart, 35 and a plurality of U-shaped steam tubes extending wholly within the said shell and having their ends connected with the said chambers.

A practical embodiment of the invention 40 is represented in the accompanying drawings forming a part of this specification, in which similar characters of reference indicate corresponding parts in both views.

Figure 1 is a longitudinal sectional elevation 45 of the hot water tank; and Fig. 2 is an enlarged transverse section of the same on the line 2—2 of Fig. 1.

In ordinary hot water tanks as now generally constructed, use is made of a steam 50 coil within a shell, the coil being usually of the same area as the pipe supplying the same, and hence the efficiency of the coil is impaired as soon as the steam condenses in the coil. The water of condensation accumulating in the first bends of the coil must 55 naturally flow through all the following ones, and with the additional condensation taking place in the remaining coil surface it frequently happens that more than half 60 of the bends are completely filled with water of condensation and hence their value as a

heating surface is destroyed. In my invention presently to be described in detail a proper expansion and distribution of the steam is had and the water of condensation 60 is not liable to remain in the steam tubes and is taken care of even should a rapid condensation of steam take place in all the steam tubes. The shell A, of boiler plate or other suitable material, is provided with 65 a cold water inlet B and a hot water outlet C. An expansion and distributing chamber D is secured to the shell A, preferably at the bottom thereof near one end, as plainly shown in Fig. 1, and the said expansion and 70 distributing chamber D is preferably in the form of a saddle having an annular flange D' bolted or riveted to the shell, as indicated in the drawings. The chamber D is provided with an integral top D² registering with a corresponding opening in the shell A, and the said chamber D is also provided with a body cover D³ bolted or otherwise fastened in place on the chamber. A pipe E screws into or is otherwise fastened 75 to the cover D³ and this pipe E is connected with a source of steam supply, either live steam or exhaust steam.

Within the shell A are arranged a plurality of independent steam tubes F, preferably made U-shape, and each having one end expanded or otherwise secured in the top D² of the expansion and distributing chamber D, while the other end of each tube is similarly connected with the top G' of a 90 condensation chamber G, similar in construction to the expansion and distributing chamber D. The condensation chamber G is saddle shaped and is provided with an annular flange G² bolted to the shell A, and the 95 chamber G is also provided with a bottom cover G³, to which is secured by screwing or otherwise a pipe H for carrying off the water of condensation to a suitable place of discharge.

When the hot water tank is in use steam 100 passes by way of the pipe E into the expansion and distributing chamber D in which the steam is free to expand and is distributed equally to the several steam tubes F 105 through which the steam passes so as to heat the tubes and thus cause a rapid heating of the water contained in the shell A. Any water of condensation that forms is discharged immediately into the condensation 110 chamber, which is of ample size to accommodate all the water of condensation that

may flow out of the pipes or form in the chamber G, it being understood that such water of condensation is immediately conducted out of the chamber G by the pipe H.

5 The hot water tank shown and described is very simple and durable in construction, and a large amount of heating surface is provided owing to the large number of individual tubes F connecting the chambers 10 D and G with each other, so that a rapid heating of the water contained in the shell A takes place. By making the steam tubes U-shaped they readily expand and contract without danger of becoming loose in the 15 tops D² and G' of the chambers D and G.

Having thus described my invention, I claim as new and desire to secure by Letters Patent:

A hot water tank, comprising a closed 20 horizontal shell having a plurality of openings in its under side adjacent each end and provided with an inlet for the cold water and with an outlet for the hot water, a steam expansion and distributing chamber attached 25 to the underside of the shell at one end thereof and depending therefrom, a condensation chamber attached to the under side of the said shell at the other end thereof and depending from the shell, each chamber having an integral top and a removable

cover at the bottom, the tops having apertures registering with the openings of the shell, an inlet pipe attached to the cover of the said expansion and distributing chamber and connected with a source of steam supply, 35 an outlet pipe connected with the cover of the said condensation chamber for carrying off the water of condensation, and a plurality of U-shaped steam tubes extending wholly within the shell and independent one 40 of the other, the said steam tubes having their ends passing through the openings of the shell and secured in the apertures of the integral tops of the said chambers so that the steam entering the said steam expansion and distributing chamber is expanded 45 therein and equally distributed to the entrance ends of the said steam tubes to pass through the latter into the said condensation chamber, the capacity of the latter being 50 ample to take care of all the water of condensation.

In testimony whereof I have signed my name to this specification in the presence of two subscribing witnesses.

FRANK L. PATTERSON.
